UNITED STATES PATENT OFFICE.

JOSEPH R. SMITH, OF WATERBURY, CONNECTICUT, ASSIGNOR TO THE WATERBURY
BUTTON COMPANY, OF WATERBURY, CONNECTICUT, A CORPORATION OF CON-
NECTICUT.

DESIGN FOR A BELT-BUCKLE.

41,814.

Specification for Design.

Patented Oct. 3, 1911.

Application filed June 23, 1911. Serial No. 635,038. Term of patent 3½ years.

To all whom it may concern:

Be it known that I, JOSEPH R. SMITH, a citizen of the United States, residing at Waterbury, New Haven county, State of Connecticut, have invented a new, original, and ornamental Design for Belt-Buckles, of which the following is a specification, reference being had to the accompanying drawings, forming a part thereof, in which the

figure is a front elevation of the belt buckle, showing my new design.

I claim:

The ornamental design for a belt buckle, as shown.

JOSEPH R. SMITH.

Witnesses:

FRED L. ROWE,
A. S. WEDGE.
